GRIPPING DEVICE FOR SHEET METAL
STRETCHING MACHINES

Ernest Lambert Tinley, Wolverhampton, England, assignor to Joshua Bigwood & Son Limited, Wolverhampton, England

Application July 24, 1947, Serial No. 763,270
In Great Britain July 5, 1946

10 Claims. (Cl. 24—263)

1

This invention relates to sheet metal stretching machines, it is well known in connection with large rolled sheets of metal that, after rolling, stresses have been set up in the sheet, and that these stresses can be removed by a stretching operation. Such sheets may be 20 ft. long and 6 ft. wide up to $\frac{1}{4}$ of an inch thick and to remove the stresses a stretching force of 400 tons or more may be required.

To apply this strain it is essential that a powerful grip on the two opposed edges of the sheet should be obtained and in order to remove the stresses for the full width of the sheets it is essential that the grip should be effective for the full width of the sheet notwithstanding variations in thickness and contour of the sheet, which obtain in practice with rolled sheets though these variations are small, say up to $\frac{1}{1000}$ of an inch.

The invention relates to stretching machines for the above purpose in which two opposed gripping jaws are provided one of which is usually stationary and the other receded by a hydraulic control which applies the strain.

The gripping devices used in this type of machine usually comprise a pair of jaws each having a pair of relatively inclined parts upon which the gripping jaws are mounted in such manner that as the strain increases so the grip is increased by the gripping members being closed by being forced inwardly between the converging inclines in the jaws.

According to this invention each grip is obtained by a pair of gripping members at least one of which extends continuously across the width of the work and is controlled by a closing device which distorts this gripping member in such manner as to grip the sheet continuously across its width notwithstanding the variation in thickness and contour which obtain in practice.

The gripping members may take the form of opposed gripping bars at least one of which extends continuously across the width of the work and is controlled by a fluid pressure closing device for the purpose of distorting this gripping bar.

The opposed gripping bars may be supported inside a recess in the main jaw member, said recess having opposed, outwardly converging, inclined surfaces and at least one of the gripping bars may be supported along its length in a plurality of blocks which are capable of movement relative to each other along one of the inclined surfaces of the jaw in such a manner as to permit distortion of this gripping bar when encountering variation in thickness and contour of the sheet.

2

Referring to the drawings.

Figure 1 is a view in side elevation of a sheet metal stretching machine embodying gripping jaws constructed in accordance with the present invention.

Figure 2 is an enlarged view of the right hand gripping jaw in Figure 1.

Figure 3 is a view in end elevation of the gripping jaw in Figure 2 in the direction in which the work enters.

Figure 4 is a section on the line 4—4 in Figure 2.

Figure 5 is an enlarged fragmentary section on the line 5—5 of the gripping jaw in Figure 3 showing the construction of the upper and lower gripping members.

Figure 6 is an enlarged section on the line 6—6 in Figure 2.

In the construction as shown in Figures 1 to 6 the lower gripper consists of a number of gripping blocks 10 secured together and extending for the full width of the machine supported upon the lower inclined surface 11 of the jaw, preferably through the medium of rollers 12 and these blocks 10 carry the gripping member proper which is in the form of a hardened steel member 13 having a serrated or roughened upper surface 14 adapted to engage with the undersurface of the sheet, this serrated member 13 being rigidly secured to the blocks 10 as by headed screws 15. Although this gripping bar 13 is described as being in one piece it may consist of a plurality of short lengths disposed end to end or alternatively the gripping blocks 10 may be constructed as one continuous block.

The upper grip blocks 16 are in short lengths, say six inches and the gripping bar 17 is mounted loosely in a slot in each of these grip blocks 16, the distortion of the bar being effected by a flexible advancement of the grip blocks 16.

These grip blocks are slidably supported beneath the upper incline 18 of the jaw and in close contact with each other and preferably again with interposed rollers 19 and extending for the full width of the machine, the control bar 20 being operated for the purpose of opening and closing the gripping device by means of a compressed air device, which conveniently comprises a piston 21 and piston rod 22 in a cylinder as generally indicated at 23, the piston rod 22 being connected to the control bar 20 by means of a pin 24. This control bar 20 is connected to the end gripping blocks 25 by links 26 so that when the control bar 20 is receded the grip will be released.

Interposed between each of the grip blocks 16

and the control bar 20 is a compression spring 27 so that when the control bar is pneumatically advanced each grip block is pushed forwardly through the medium of the spring 27 and thus forces the gripping bar 17 into contact with the upper surface of the sheet. With variations in the thickness or contour of the sheet one portion or portions of the gripping bar 17 will engage before the remainder of the bar engages, so that further movement of the corresponding grip block or blocks is resisted but the other grip blocks continue to advance pushing corresponding parts of the gripping bar forwardly and distorting it so as to provide a continuous grip on the sheet.

This gripping bar may be conveniently of hardened steel 1½ ins. wide, 1⅓ ins. deep, secured to each grip block by a screw 23 and spring washer in such manner as to leave freedom of movement between the bar and the gripping blocks, there being a small clearance of say $\frac{1}{2}$ in. between the width of the slots in the gripping blocks 16 and the width of the gripping bar 17.

Conveniently each grip block 16 may be secured to the control bar 20 by a headed screw 29 passing through the grip block and entering the control bar, this screw being free to slide through the grip block when the control bar 20 is advanced, the rear portion of the grip block 16 being recessed to receive the compression spring 27.

The cylinder of the pneumatic gripping control 23 has its axis parallel to the upper incline 18 of the jaw member and so arranged that the gripping mechanism for the upper surface is held in contact with the upper incline 18, so positively opening the jaw when the mechanism is receded.

The one gripping jaw 30 is preferably stationary when in use though provided with a pneumatically controlled gripping device 23 as previously described and the other jaw 31 adapted for sliding movement under hydraulic control such as the piston and cylinder arrangement generally indicated at 32. The stationary jaw 30 is, however, provided with screws 33 or other adjustment so that its position can be altered according to the length of sheet to be treated.

The main jaw member 34 is preferably a steel casting extending for the full width of the machine the two inclined surfaces 11 and 18 previously referred to, being constituted by liner plates 35 and 36 of hardened steel secured to the main jaw by studs 37 and 38.

The upper liner plates 35 are preferably made in short lengths, i. e. of a less length than the grip blocks 16. Each grip block is cut away and provided at each end with an angle plate 39 presented upwardly and inwardly so as to overhang and engage with a cut away portion 40 of the upper surface of the liner plate 35 thereby providing a sliding support for the grip blocks. The upper inclined surfaces of the grip blocks are recessed at 41 to receive a plurality of rollers 19, the ends of which are located by the angle plates 39.

The lower liner 36 may be in a single piece extending for the full width of the machine or in shorter lengths, being provided at intervals on its upper surface with strips 42 which locate the supporting rollers 12 beneath the lower gripping member.

Means are provided for adjusting this lower gripping member in relation to the jaw to enable the machine to be more effectively used with sheets of different thicknesses, such means consisting of screws 43 and distance pieces 44 pass-

ing through each lower gripping block and abutting against the part 45 of the main jaw.

The main jaw member 34 is provided with end cover plates 46 for retaining the grip members in place but cut away at 47 to permit the insertion of the sheet.

In practice the one gripping jaw 30 is adjusted along the machine according to the length of the sheet to be treated and the lower grip members are pre-set according to the thickness of the sheet. The sheet is then inserted between the gripping bars 13 and 17 and each upper gripping mechanism is then closed through the medium of the compressed air devices 23, the serrated gripping bars engaging with the upper and lower surfaces of the sheet, local variations in thickness and contour of the sheet resulting in some of the upper grip blocks 16 moving forward further than others, thereby distorting the upper gripping bars until they provide a continuous grip or substantially continuous grip throughout the full length of the jaws.

The hydraulic mechanism 32 is then operated so that the two jaws are separated and the initial grip obtained by the compressed air device is then taken over by the strain on the sheet which causes the upper and lower gripping members to travel along the converging inclines so that the greater the strain applied for stretching the metal, the greater will be the grip, the distortion of the gripping bars being maintained by reason of their initial engagement, the teeth on the gripping bars having entered the surfaces of the sheet.

What I claim then is:

1. In a gripping device for sheet metal stretching machines, a main jaw member having a recess therein, a surface of said recess being inclined; a plurality of movable blocks arranged side by side across the width of the main jaw member and supported in sliding engagement with said inclined surface; a gripping member extending continuously across the width of the main jaw member and supported in said blocks, and means for distorting this gripping member in such manner as to provide a continuous grip across the width of the work.

2. In a gripping device for sheet metal stretching machines, a main jaw member having a recess with opposing, outwardly converging inclined surfaces; a plurality of movable blocks arranged side by side across the width of the main jaw member and supported in said recess in sliding engagement with said inclined surfaces; opposed gripping members supported in said movable blocks one of said gripping members extending continuously across the width of the main jaw member, and means associated with the said continuous gripping member for distorting this member in such manner as to provide a continuous grip across the width of the work.

3. In a gripping device for sheet metal stretching machines, a main jaw member having a recess therein; opposed sets of movable blocks arranged side by side across the width of the main jaw member and supported in said recess; opposed gripping members supported in said movable blocks one of said gripping members extending continuously across the width of the main jaw member; a control device having a yielding connection with the set of blocks which supports the said continuous gripping member, and means for actuating said control device so as to displace the blocks connected therewith.

4. In a gripping device for sheet metal stretch-

ing machines, a main jaw member having a recess therein; opposed sets of movable blocks arranged side by side across the width of the main jaw member and supported in said recess; a pair of gripping members supported each in one of said sets of blocks one of said gripping members extending continuously across the width of the main jaw member; a control bar connected to the set of blocks which supports the said continuous gripping member; spring means interposed between said blocks and the control bar, and means for actuating said control bar so as to displace the blocks connected therewith in such manner as to distort the continuous gripping member supported in said blocks.

5. In a gripping device for sheet metal stretching machines, a main jaw member having a recess therein; opposed sets of movable blocks arranged side by side across the width of the main jaw member and supported in said recess; opposed gripping members supported in said blocks one of said gripping members extending continuously across the width of the main jaw member; a control bar associated with the set of blocks which supports the said continuous gripping member; links connecting the outermost blocks of said set to the control bar; spring means interposed between the remaining blocks of said set and the control bar; and means for actuating said control bar so as to displace the blocks associated therewith in such manner as to distort the continuous gripping member supported in said blocks.

6. In a gripping device for sheet metal stretching machines, a main jaw member having a recess there; opposed sets of movable blocks arranged side by side across the width of the jaw member and supported in said recess; a pair of opposed gripping members supported in said blocks one of said gripping members extending continuously across the width of the main jaw member; a control bar associated with the set of blocks which supports the said continuous gripping member; means for actuating said control bar so as to displace the blocks associated therewith, such means comprising a rod connected to the control bar and a fluid pressure device adapted to actuate said rod so as to displace the blocks through the medium of the control bar.

7. In a gripping device for sheet metal stretching machines, a main jaw member having a recess therein; opposed sets of movable blocks arranged side by side across the width of the main jaw member and supported in said recess; a gripping member extending continuously across the width of the main jaw member and loosely mounted in the one set of blocks; a gripping member fixed in the other set of blocks; and means for distorting the loose continuous gripping member in such manner as to provide a continuous grip across the width of the work.

8. In a gripping device for sheet metal stretching machines, a main jaw member having a recess therein; opposed sets of movable blocks arranged side by side across the width of the main jaw

member and supported in said recess; opposed gripping members supported in said blocks one of said gripping members extending continuously across the width of the main jaw member; means for distorting the said continuous gripping member in such manner as to provide a continuous grip across the width of the work, and means for adjusting the other gripping member in relation to the main jaw member in order to accommodate metal sheets of different thicknesses.

9. In a gripping device for sheet metal stretching machines, a main jaw member having a recess with opposed, outwardly converging, inclined surfaces; opposed sets of movable blocks supported in sliding engagement with said inclined surfaces; a gripping member loosely supported in one set of blocks; a gripping member fixed in the opposing set of blocks; a control bar associated with the blocks supporting said loose gripping member; links connecting the outermost blocks of said set to the control bar; spring means interposed between the remaining blocks of said set and the control bar; each of said remaining blocks having a headed pin passing therethrough, being slidable therein, and being secured to the control bar; a rod connected to said control bar, the axis of said rod being approximately parallel to the inclined surface engaged by said set of blocks; and means for actuating said rod so as to advance and retract the control bar causing movement of the associated blocks in such manner as to distort the gripping member supported therein when encountering variations in thickness and contour of the work, so as to provide a continuous grip across the width of the work.

10. In a sheet metal stretching machine, two opposed main jaw members; each jaw member having a recess therein; a plurality of movable blocks arranged side by side across the width of the main jaw member and supported in said recess, a pair of gripping members supported in said blocks, one of said gripping members extending continuously across the width of the main jaw member recess means for distorting the said continuous gripping member of each pair so as to obtain a continuous grip across the width of the work for each jaw; means for advancing and retracting one of said jaws with respect to the other jaw and means for adjusting the position of said other jaw in order to accommodate different lengths of work.

Patent No. 2,522,319

September 12, 1950

ERNEST LAMBERT TINLEY

It is hereby certified that error appears in the above numbered patent requiring correction as follows:

In the grant, line 14, strike out the words "of seventeen years"; same line, after "grant" insert *until July 5, 1966*; in the heading to the printed specification; line 9, before "10 Claims." insert the following:

Section 1, Public Law 690, August 8, 1946. Patent expires July 5, 1966
and that the said Letters Patent should be read as corrected above, so that the same may conform to the record of the case in the Patent Office.

Signed and sealed this 28th day of November, A. D. 1950.
